UNITED STATES PATENT OFFICE.

WILLIAM L. SMITH, JR., OF NASHVILLE, TENNESSEE, ASSIGNOR TO MAY HOSIERY MILLS, OF NASHVILLE, TENNESSEE, A CORPORATION OF TENNESSEE.

STOP MOTION FOR KNITTING MACHINES.

Application filed March 22, 1924. Serial No. 701,208.

My said invention relates to a needle stop motion for knitting machines adapted to stop the machine on the breaking of a dial needle or the latch or butt of a cylinder needle or when for any reason the yarn becomes piled up on the needles or on occurrence of a loose yarn. It is an object of my invention to provide a stop motion of this character which shall be simple, 10 cheap and effective and which can be applied to various types of knitting machines now in use though it is peculiarly adapted for use with a rib knitting machine having provision for knitting round and round at 15 certain times and reciprocating at others, thus knitting, e. g., stockings with rib tops and plain feet.

Referring to the accompanying drawings, which are made a part hereof and on which 20 similar reference characters indicate similar parts,

Figure 1 is an elevation of a knitting machine with the device of my invention in place thereon, parts being broken away for 25 clearness,

Figure 2 a section on line 2—2 of Figure 1,

Figure 3 a section on line 3—3 of Figure 1, and

Figure 4 is a detail of a lever shown in 30 Figure 1.

In the drawings reference character 10 indicates a support of ordinary type for the knitting machine head, 11 the latch ring support, 12 the sinker cam ring, 13 the latch ring, 14 the dial, and 15 the dial cam cap, all of said parts being of the ordinary type familiar to those skilled in the art. On the cam cap I provide a bent lever pivotally supported by means of a screw 16. The bent 40 lever comprises a horizontal arm 17, another horizontal arm 18 and a vertical arm 19 terminating in a point which may be slightly curved to form a sort of hook projecting in the direction of rotation of the head. This point is within the circle of cylinder needles and just above the plane of the dial needles so that any accumulation of yarn on needles of either bank will catch the point of the 45 depending arm, whether hooked or not, and will swing the lever about its pivot 16. The horizontal arm 17 at its free end normally rests in a slot in a vertically extending cylindrical guide 20 and engages an annular notch in a plunger 21, thus holding the 55 plunger down against the action of a spring

22 tending to raise the same. Midway of its length the plunger has a pin 23 projecting through a slot in the guide for manually returning it against the action of the spring into position to be held by arm 17. At its 60 upper end the plunger carries a disk 24 held in place by a screw 25 so as to be free to rotate on the latter.

On a fixed part of the machine above the dial cap a lever 26 is supported on a pivot 27, this lever having a projecting contact finger 28. The contact device is pivoted on lever 26 by a pin 29 in a manner to permit the device to swing freely relatively to the lever 26 in one direction while it is held rigidly against movement relatively to the lever in the other direction. Should the disk 24 be raised during reciprocating knitting it will strike against the finger 28 providing the machine is moving forward, i. e., in the direction of ordinary rotation for knitting round and round and will swing the lever 26 about its pivot and through a series of links and pivoted disks 30, 31, 32, 33 and 34 will swing a detent 35 on its pivot 36 in a direction to withdraw the same from a notch in a plunger 37 of a stop motion of conventional type. This permits the plunger to fall and arrest the operation of the machine in ordinary manner. If the cams are moving 85 backward, i. e. clockwise or in the reverse of the ordinary direction for knitting, the finger 28 will swing on its pivot 29 to let the roller pass and then will resume its working position, so as to trip the stop motion on the 90 return of the roller with the knitting cams.

The point of the bent lever at the end of the vertical arm 19 is preferably located just inside the circle of cylinder needles and extends down far enough to strike a bent dial needle or one that is projected when it should be retracted. The latter contingency will occur for instance if a dial needle should have its butt broken off and so remain in projected position. Preferably also the bar 19 will be arranged slightly in rear of the needle wave of the dial needles so as to catch a defective needle or broken thread or other defect as soon as possible after its occurrence and thus stop the machine without unnecessary delay.

It will be obvious to those skilled in the art that certain features of my invention may be modified in various ways and therefore I do not limit myself to the specific mechanism 110

shown in the drawings and described in the specification but only as indicated in the appended claims. For example the device is here shown as applied to a machine having a stationary needle cylinder, but may also be used on a machine with a rotary needle cylinder.

Having thus fully described my said invention, what I claim as new and desire to secure by Letters Patent, is:

1. A stop motion for knitting machines comprising a feeler arranged within the circle of cylinder needles traveling within said circle, a vertically movable plunger, means tending to move the plunger upward, a detent for the plunger operated by said feeler, and means adapted to be actuated by said plunger when released for stopping the machine, substantially as set forth.
2. A stop motion for knitting machines comprising a support within the circle of cylinder needles, a feeler pivoted thereon and extending close to the needle circle, an upwardly movable device normally held down by the feeler, a lever mounted above said upwardly movable device and adapted for actuation thereby when released, and connections from said lever for stopping the machine, substantially as set forth.
3. A stop motion for dial and cylinder knitting machines comprising a plunger on the dial cam cap, a detent for holding said plunger in one position, a feeler within the needle circle and adjacent the plane of the dial needles adapted to release said detent and means adapted to be actuated by the plunger when released for stopping the machine, substantially as set forth.
4. A stop motion for dial and cylinder knitting machines comprising a plunger supported for vertical movement on the dial cam cap, a spring for moving it upward, a horizontally movable detent engaging said plunger for holding it down, a feeler inter-

gral with the detent and located adjacent the intersection of the dial and cylinder needles and means on a stationary part of the machine adapted to be engaged by said plunger when released for stopping the machine, substantially as set forth.

5. A stop motion for dial and cylinder knitting machines comprising a plunger on the dial cam cap adapted to move up and down, a detent for holding it in one position, a feeler adapted to release the detent, a lever on a fixed part of the machine adapted to be moved by the released plunger in one direction of rotation to stop the machine and a finger on said lever adapted to be moved independently thereof on a reverse rotation of the machine, substantially as set forth.

6. A stop motion for dial and cylinder knitting machines comprising a bearing on the dial cam cap, a plunger vertically movable in the bearing, a spring to force the plunger upward, a detent for the plunger having a point adjacent the verge of the forming fabric, and means operable by the plunger when raised for stopping the machine, substantially as set forth.

7. In a knitting machine, a stationary needle cylinder, a stationary dial, a rotary dial cam cap, and a latch-ring, in combination with a feeler supported within the needle circle adjacent the verge of the forming fabric, tripping means within the needle circle controlled by said feeler, and connections to a stop motion of conventional type including an element on a fixed part of the machine in the path of said tripping means when the tripping means is released by said feeler, substantially as set forth.

In witness whereof, I have hereunto set my hand at Nashville, Tennessee this 13th day of March, A. D. nineteen hundred and twenty-four.

WILLIAM L. SMITH, JR.
